UNITED STATES PATENT OFFICE.

CHARLES G. McCUAULLEY, OF JACKSONVILLE, FLORIDA.

RAIL BOND.

Application filed December 12, 1923, Serial No. 680,097. Renewed May 16, 1928.

The bonding of track circuits in railway signalling presents problems which have not yet been satisfactorily solved. Probably the most satisfactory type of bond in use today 5 is a flexible multi-strand cable having its ends soldered to terminal pieces attached to proximate rails and confined between its ends by clips which hold the cable along the top of the splice bar and prevent, to some extent, the vibratory movements which are the usual cause of fracture. Strap bonds cut 10 from sheet metal have been proposed but none have proved to be practical in use. The present invention is concerned with the provision 15 of a reinforced strap bond which shall be of simple and inexpensive construction for manufacture and shall meet the requirements of a satisfactory bond in that it shall be of such form and so mounted as to be free from 20 fracturing vibration, of low resistance and high conductivity, and mounted entirely clear of the splice bars, track bolts, joint spikes, etc., and accessible at all times for purposes of inspection or repair while not interfering 25 with the inspection or replacement of any of the other parts enumerated.

In accordance with the invention it is proposed to form the bond as an article of manufacture comprising a single integral unit 30 adapted to have its ends joined with adjacent rails and to connect the rail electrically while it is held entirely clear of the splice bars, track bolts and joint spikes, and affording free accessibility to such parts for 35 maintenance. The maintenance of bonding in connection with track circuits in railway signalling is a substantial item of expense entailing constant inspection and frequent replacement of defective bonds. Contrary- 40 wise, any association of the bonding with the splice bars, track bolts or joint spikes materially increases the cost of initial assembling and maintenance of the respective parts because of their interdependence. By the 45 improved construction it is proposed that such interdependence shall be eliminated and the improved strap bonds mounted in such relation to the rail and to the retaining and supporting parts thereof as to permit access to 50 such parts without interference. The improved bond is mounted in the preferred construction and reinforced throughout the greater part of its length to prevent lateral bending and to concentrate the longitudinal 55 movement of the bond due to expansion and contraction of the rails in compensation,

bends are provided at each end. This construction elevates the bond above the splice bars, track bolts and joint spikes and renders it relatively free from the splashing of 60 brine or water from the track bed.

The invention will be described in greater particularity hereinafter in connection with the illustrated embodiment of the preferred form shown in the drawings, wherein: 65

Figure 1 is a view in side elevation of parts of two rails showing the application of the improved bond thereto and its relation to the splice bar therefor, bolts and track spikes.

Figure 2 is a transverse sectional view 70 through one of the rails taken on the plane indicated by the line 2-2 of Figure 1 and looking in the direction of the arrows and showing suitable means for fastening the improved bond thereto. 75

Figure 3 is a fragmentary detailed view in section through one of the ferrules of the bond showing the means for anchoring it.

Figure 4 is a fragmentary view in perspective showing the bend and one ferrule. 80

Figures 5-8 are views showing suitable alternative cross sectional forms which the bond may be given.

As this description proceeds it will be evident that the improvements herein do not 85 reside merely in the provision of a bond of wide cross-sectional area (specially rolled) but rather in the formation of such a bond of such means as permit it to be mounted more advantageously on adjacent rails to 90 provide accessibility without interference to the splice bar, bolts and spikes, and conduct the signalling current with minimum power consumption and losses from one track rail to another. The improved bond considered as an article of manufacture consists of an extended section *a* having three 95 bends at each end, the first one of which *a'* carries the metal back on itself in the same plane as the section *a*, the second of which *a''* carries the metal at right angles from the section *a* but in parallelism therewith and the third one of which *a'''* carries the metal back across the plane of the section *a* and at right angles thereto terminating in means 100 for anchoring the bond to the rails *b*, *c*, respectively, such means in the illustrated embodiment being shown as split ferrules *a''*. In the simplest and most inexpensive form the bond described is made from soft steel 105 or iron wire with low carbon content and rolled to suitable cross sectional forms as 110

shown. The conductivity is high and the resistance low. While it has been proposed heretofore to employ metallic bonds these have not been constructed in the form described nor have they been employed and mounted as elements wholly independent of associated parts of the rail mounting. Accordingly, they have not served the principal purposes with which the improvements are concerned, 10 to wit, elimination of vertical vibration and resultant fracture, freedom from interference with the application or removal of splice bars, bolts and track spikes, and mounting in an elevated position with respect to the 15 track bed. As shown in Figure 1 the rail sections *b*, *c*, are united by splice bars *e*, *f*, in accordance with established practice which are bolted through by bolts *g*. The rail sections are held on the ties *h* by track 20 spikes *i*. As an important factor in track maintenance it is desirable that the splice bars, bolts and track spikes, be accessible for inspection or replacement without interference by the bond and contrary-wise that 25 the bond be mounted wholly independently of all of such units. These results are attained by mounting the improved bond with its section *a* in intimate contact with the outer sides of the head of the rails *b*, *c*, and 30 wholly above the splice bars *e*, *f*, bolts *g*, and track spikes *i*. This relationship is secured by introducing the ferrules *a*⁴ at the ends of the bond through holes provided therefor in the web sections of the rails *b*, 35 *c*, at points beyond the ends of the splice bars *e*, *f*, and at a substantial distance above the track spikes *i*. The upwardly extending bends *a*² hold the section *a* of the bond in its elevated position and the bends *a*¹ not 40 only permit expansion and contraction without injury or displacement of the bond but impress a spring action thereon to hold the section *a* yieldingly in intimate contact with the faces of the rails. The invention is not 45 to be limited to the particular means employed for securing the bond to the rails but those illustrated have been found simple and effective in practice. The ferrules *a*⁴ terminate in flanges *a*⁵ which may be upset 50 as indicated in Figure 3 after the ferrules are introduced through the respective openings in the rail webs, and tapered pins *h* may then be driven into the open ends of the split ferrules so as to expand them into 55 intimate engagement with the wall of the opening. The anchorage is at once secure and effective and insures an efficient electrical union between the rails and the bond over a large superficial area so as to introduce 60 a factor of minimum resistance at these points. The large cross sectional area of the bond throughout the rest of its length insures maximum conductivity. Since the

section *a*, which is the body portion of the bond, is vertically disposed and is pressed 65 yieldingly against the faces of the rails it is not subject to vertical vibrations and resultant fracture. The bends in the bond enable it to conform yieldingly to any relative movements between the rail sections in 70 lateral and horizontal planes. The elevated position of the bond protects it from the injurious influences of brine and water drippings from ears and splashings from the 75 rail bed.

In Figures 5-8 alternative cross sectional forms of the strip *a* are indicated which give, in fact, greater cross sectional area and correspondingly less resistance. The forms shown in Figures 5 and 6 for a given cross 80 sectional area enable the width of the strap to be less so that the clearance between it and the splice bar may be actually greater. This may be desirable under some conditions of use.

As indicated hereinbefore, the invention is not to be limited to the particular form of the bends employed nor to the means for mounting the strap bond on the rails since 90 one skilled in the art may depart from the teaching of the drawings without avoiding the spirit of the invention.

What I claim is:—

1. In combination with two rails and splice bars and bolts to connect their ends, a stiff 95 strap bond of metal having an elongated section in engagement with the outer faces of the rails and clearing the tops of the splice bar and terminating at its ends in bends extending downwardly and inwardly, means 100 formed at the ends for engagement with the respective rails to support the elongated section above the splice bar, said bends serving to press the elongated section yieldingly against the face of the rails.

2. In combination with two rails and splice bars and bolts to connect their ends, a stiff unitary rail bond of rolled metal having an elongated section formed in cross section of greater height than width, said elongated 110 section clearing the top of the splice bar and being in yielding engagement with the outer faces of the heads of the rails and terminating at its ends in bends extending downwardly and inwardly, and means formed at 115 the ends for connection with the webs of the respective rails to support the elongated section above the splice bar, said bends serving to maintain the yielding engagement of the elongated section with the outer faces of the heads of the rails and to provide for expansion.

This specification signed this 1st day of December, A. D. 1923.

CHARLES G. McCaulley.
